Primary Examiner—Stacia Cadmus(74) *Attorney, Agent, or Firm*—MacMillan, Sobanski & Todd, LLC(57) **CLAIM**

The ornamental design for a mirror, as shown and described.

DESCRIPTION

FIG. 1 is a front perspective view of a mirror according to the present design;

FIG. 2 is a back perspective view thereof;

FIG. 3 is a front elevational view thereof;

FIG. 4 is a top plan view thereof;

FIG. 5 is a bottom plan view thereof;

FIG. 6 is a first side elevational view thereof; and,

FIG. 7 is a second side elevational view thereof.

The broken lines shown FIGS. 2 and 5 are illustrative of environmental structure only and form no part of the claimed design.
